[57] **CLAIM**

The ornamental design for a T-Astragal with sidelock flushbolt, as shown and described.

DESCRIPTION

FIG. 1 is a front elevational view of my T-Astragal with sidelock flushbolt showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a front elevational view with the bolt extended. The bolt within the T-Astragal shown in FIG. 2 in phantom forms no part of this design.

The claimed design is shown broken away to indicate indefinite length.
